UNITED STATES PATENT OFFICE.

ROBERT H. HUMMERT, OF DAYTON, OHIO.

DESIGN FOR A RADIATOR-CAP.

58,908.

Specification for Design.

Patented Sept. 6, 1921.

Application filed May 16, 1921. Serial No. 470,015. Term of patent 14 years.

To all whom it may concern:

Be it known that I, ROBERT H. HUMMERT, a citizen of the United States, residing at Dayton, county of Montgomery and State of Ohio, have invented a new, original, and ornamental Design for a Radiator-Cap, of which the following is a specification, reference being had to the accompanying drawing, forming part thereof.

Figure 1 is a plan view of the radiator cap showing my new design.

Fig. 2 is a side elevation thereof.

I claim:

The ornamental design for a radiator cap, as shown.

ROBERT H. HUMMERT.
